UNITED STATES PATENT OFFICE.

CHARLES L. ANDERSON, OF WILLIMANTIC, CONNECTICUT.

DESIGN FOR A BADGE.

SPECIFICATION forming part of Design No. 25,908, dated August 11, 1896.

Application filed May 28, 1896. Serial No. 593,513. Term of patent 3½ years.

To all whom it may concern:

Be it known that I, CHARLES L. ANDERSON, a citizen of the United States of America, residing at Willimantic, in the county of Windham and State of Connecticut, have invented and produced a new and original Design for Badges, of which the following is a description, reference being had to the accompanying drawing.

5 The design consists of the figure of a man mounted on a bicycle, with the head on a distinctly larger scale than the other parts of

the body. The bicycle-wheels are supported on the plates or scales of a balancing device. These figures above referred to may be 15 mounted upon a circular disk, as shown in the accompanying illustration.

What I claim is—

The design for a badge substantially as illustrated and described.

CHARLES L. ANDERSON.
